UNITED STATES PATENT OFFICE.

CARTTER WEAVER, OF PITTSBURGH, PENNSYLVANIA.

COLLAR BUTTON.

Application filed November 1, 1922. Serial No. 598,396.

To all whom it may concern:

Be it known that I, CARTTER WEAVER, a citizen of the United States, residing at Pittsburgh, in the county of Allegheny and State of Pennsylvania, have invented certain new and useful Improvements in Collar Buttons, of which the following is a specification.

This invention relates to shirt studs or collar buttons, and is an improvement upon the construction shown, described and claimed in my prior application for collar button, filed November 5, 1921, Serial No. 513,066.

15 The object of the present invention is to provide a collar button of the same general type illustrated in my said prior application, but particularly arranged for effective reduction in girth of a shirt neckband and enabling a normal or properly sized collar to be used with an over-sized shirt or one in which a neckband has stretched or the button holes have become torn or enlarged.

25 Further objects of the invention are in part obvious and in part will appear more in detail hereinafter.

In the drawings, Fig. 1 represents a front view of one embodiment of the invention as the same lies in place when worn; Fig. 2 is a side elevation from the left in Fig. 1; Fig. 3 is a sectional elevation on the line 3—3, Fig. 1, looking in the direction of the arrows and illustrating the collar stud elevated; Fig. 4 is a sectional plan view on the line 4—4, Fig. 2 and illustrating the button and button hole strips of a shirt in place; and Figs. 5, 6 and 7 are views corresponding respectively to Figs. 4, 1 and 2 and illustrating a modification.

40 In the description and claims hereafter the button will be described assuming it to be in place upon the wearer and the words "horizontal," "vertical," "right," "left," etc., should be so understood, also, "front" means outwardly from the neckband and "back" or "rear" means toward the neck.

The button shown in the drawings comprises a base or body portion 1 shown as a rounded metal plate on which are supported a suitable number (three being shown) of studs to which the ends of the shirt neckband and collar are attached. More particularly, the button includes a centrally disposed stud 2 adapted to receive or to extend

5 through the button holes in both ends of the collar and on either side of which are located a "right" stud 3 and a "left" stud 4 adapted to respectively receive or to be passed through the button hole at the upper ends of the button hole strip 5 and button strip 6 respectively, of the shirt. Therefore, notwithstanding abnormal overlapping at the neckband of the button and button hole strips, as shown in Fig. 4, and a consequent reduction in effective girth of the shirt neckband, the collar ends attached to the stud 2 are symmetrically arranged and centrally disposed relative to the studs 3 and 4. In this respect the button here shown is similar to that of my prior application 70 above referred to.

Provision is made for abnormal overlapping of the button hole and button hole strips, for which purpose the studs 3, 4, while lying at the same horizontal level, are offset relative to each other from front to rear, and more particularly the right hand stud 3 for receiving the button hole strip is advanced or in front of the left hand stud 4 for receiving the button strip. In the arrangement shown in Figs. 1 to 4, inclusive, the stud 4 projects forwardly from the front of the base plate to which it is vertically attached in any suitable manner, such as by riveting. The stud 3 is shown as directly attached to an arm 3^a which extends around the upper horizontal edge of the shirt neckband and the body portion of which lies upwardly with the back plate 1, as shown in Fig. 2. In the form shown in Figs. 5, 6 and 7 the left hand stud 4 extends rearwardly from the main body plate 1 and the right hand stud 3 extends forwardly therefrom, so that both studs are directly attached to the back plate 1 and no arm, such as the arm 3^a, is required. Either form enables the two ends of the shirt neckband to be abnormally overlapped and the effective girth of the neckband to be reduced.

The stud 2 to which the ends of the collar are connected also lies at the same horizontal level as the studs 3, 4 but is off-set toward the front therefrom because the collar lies outside of the shirt neckband. This collar receiving stud is therefore also carried by a suitable member extending around an edge of the shirt neckband and in the form shown in the drawings is carried by an arm 7 supported at the upper edge of the plate 1 and extends downwardly and upwardly thereto.

Said arm may be rigid or detachably connected to the back plate, such as by a simple snap fastener device, but in the drawing is shown as arranged on a button 8 carried by 5 flange 9 of the back plate.

In use of the device the two ends of the shirt neckband are attached to their respective studs 4 and 3 in abnormally overlapped relation, as shown in Figs. 4 and 5. During 10 this operation the arm 7 carrying the collar stud is held elevated. Said arm is then dropped to the position shown in Figs. 1 and 6 and the ends of the collar are attached to the stud 2 in the usual manner.

15 This button is a simple shirt size reducing button which can be made at low cost and of any suitable material and which is not thick or bulky and takes little more room if any than the ordinary collar button.

20 What I claim is:

1. A collar button, comprising a body portion provided with a plurality of neckband and collar receiving studs, and means extending around the upper horizontal edge of 25 the shirt neckband for supporting two of said studs.

2. A collar button, comprising a base or body portion, three studs carried thereby, one for receiving the collar ends and two 30 others for receiving each an end of the shirt neckband, and means extending around the upper edge of the shirt neckband for supporting at least one of said studs.

3. A collar button, comprising a base or 35 body portion, three studs carried thereby, one for receiving the collar ends and two others for receiving each an end of the shirt neckband, and means extending around the upper edge of the shirt neckband for supporting two of said studs.

40 4. A collar button, comprising a base or body portion, three studs carried thereby, one for receiving the collar ends and two

others for receiving each an end of the shirt neckband, and means extending around the 45 upper edge of the shirt neckband for supporting a collar stud and at least one of the shirt neckband studs.

5. A collar button, comprising a base or body portion, three studs carried thereby, 50 one for receiving the collar ends and two others for receiving each an end of the shirt neckband, an arm extending around the upper edge of the shirt neckband for carrying a stud, and another arm extending around 55 the upper edge of the shirt neckband for carrying one of said neckband studs.

6. A collar button, comprising a base, right and left neckband receiving studs connected thereto, the right stud being off-set 60 forwardly from the left stud, and a collar receiving stud also carried by said base.

7. A collar button, comprising a base, right and left neckband receiving studs connected thereto, the right stud being off-set 65 forwardly from the left stud, and means extending around the upper edge of the shirt neckband for carrying said right neckband stud, and a collar stud also carried by said base.

70 8. A collar button, comprising a base, right and left neckband receiving studs carried thereby, the right stud being off-set forwardly from the left stud, and a collar receiving member extending around the upper 75 edge of the shirt neckband.

9. A collar button, comprising a base, right and left neckband receiving studs carried thereby, the right stud being off-set forwardly from the left stud, and a collar receiving member extending around the upper edge of the shirt neckband and hinged to 80 said base.

In testimony whereof I hereby affix my signature.

CARTTER WEAVER.
